ELECTRICAL CONDENSER

Original application filed May 27, 1924, Serial No. 716,107. Divided and this application filed March 30, 1926. Serial No. 98,412.

This application is a division of my application Serial No. 716,107, filed May 27, 1924.

This invention relates to improvements in electrical condensers, particularly of the type wherein sheets of dielectric and conducting foils are built up in a stack, the dielectric sheets being preferably at present of mica.

10 The invention relates more particularly to condensers designed to carry high currents of, say, ten amperes more or less and upwardly to hundreds of amperes; although certain structures embodying the invention 15 are useful also for high potential service whether or not large currents be used. The invention is particularly useful with alternating currents of high amperage and high frequencies such as radio frequencies, as 20 well as for high potentials.

Heretofore in condensers of the foil-stack type, in designing the same for use with currents of more than a few amperes, it has been necessary to increase greatly the number 25 of dielectric sheets, for the sole purpose of preventing serious over-heating of the condenser by such high currents. Inasmuch as good quality dielectric sheets for condenser work, such as good quality of the preferred mica sheets, is very expensive (i. e., many times more expensive than metal), and inasmuch as the amount of mica necessary to prevent over-heating by the high currents increases very rapidly with the

30 amperage employed, the cost in mica for such high current mica-and-foil condensers has been very high heretofore. The reason why the use of a much larger quantity of dielectric sheets resulted in preventing undue 35 heating of the condenser by high currents was the consequent reduction of current per sheet and therefore the reduction of the watt loss per sheet, the total watt loss being distributed throughout the increased

40 number of sheets, thereby providing a larger dissipating surface of the stack, i. e., such surface comprising the margins of the mica sheets exposed from the foil-armature sheets in the stack. In order to maintain the originally desired capacity of the condenser

when thus increasing the number of dielectric sheets, it was usually necessary to divide the stack into several serially-connected sections whereby the voltage per section was reduced and whereby also were reduced the losses due to brushing resulting from high voltage. The greater part of the increase in dielectric sheets to prevent over-heating by high currents was due to such series-sectional construction.

55 The principal and important object of the invention is to reduce the quantity of dielectric, such as mica, in condensers designed for high current duty. Other minor but valuable objects and results will be disclosed 60 in connection with the drawings.

65 The invention consists, among other things, of a foil-stack condenser construction or the equivalent wherein the heat developed by the high alternating currents used is so efficiently conducted away from the stack as to make it unnecessary to increase the number 70 of dielectric sheets (quantity of mica) for the purpose of causing, for each sheet, a lower heat generation and a higher heat-dissipation. In a certain sense, the invention involves to a certain extent the substitution of 75 masses of metal constituting heat-absorbing, heat-conducting and heat-dissipating means, in lieu of the addition of much more expensive dielectric sheets.

80 Of the drawings, Fig. 1 is a side elevation, partly in section, of the embodiment of the invention;

Fig. 2 is a sectional plan of Fig. 1 at lines 85 8-8 thereof, and

Fig. 3 is an exploded diagram showing the paths of the current thru the conducting foils of the two stack units connected in parallel.

90 There is shown an embodiment of the invention in a foil-armature and mica sheet condenser stack wherein the benefit of the thermal connection between the broad surfaces of the projecting foil-bunches and metal heat-conducting and heat-dissipating members, (such as and including the metal stack-clamps shown), is obtained by way of 95 four projecting foil-bunches in a single clamped condenser unit, as distinguished 100

from the ordinary arrangement in a stack condenser, of two foil-bunches.

In this form shown for illustration, there are two condenser stack sections A and B in the clamped condenser unit, these units being electrically and thermally connected in parallel with one another, and with an insulating separator S between them. Metal members C1, C2 engage the end faces of the double stack and are held together by bolts B1 in their clamping positions. Insulating bushings I around bolts B1 insulate stack clamps C1 and C2 from one another. The parallel current paths through stack-units A and B are indicated most clearly in diagrammatic Fig. 3, with its arrows. Current enters terminal T1, say, and there divides. One path of the current extends from terminal T1 and through upper stack-clamp C1, to foil-bunch F1 of stack-unit A, to the interior of A itself, across the dielectric sheets to the oppositely poled foil-bunch F2, to and out of A via terminal T2. The other and parallel current path extends from terminal T1 through foil-bunch F3 of stack-unit B, to the interior of B itself, across the dielectric sheets to the oppositely poled foil-bunch F4, to lower stack-clamp C2, and to and out terminal T2. Thus both paths extend in parallel thru stack units A and B respectively en route from terminal T1 and stack-clamp C1 to terminal T2 and stack-clamp C2.

Referring to Figs. 1-2, (showing more of the structure yet in Fig. 1 somewhat exploded for clearness) right-hand projecting foil-bunch F3 of lower stack unit B (Fig. 1) is clamped to upper stack-clamp C1 and to terminal T1, by means of auxiliary foil clamp member K1 and its bolts L1. Thus not only is terminal T1 electrically connected to foil-bunch F3, but that foil-bunch is clamped in good thermal connection with upper stack-clamp C1, so that the latter is a stack-terminal as well as a stack-clamp, the effect being that terminal T1 is provided, via heat-dissipator C1, with substantial heat-dissipating area exposed from the interior of the stack. The right-hand projecting foil-bunch F2 of upper stack unit A is clamped to lower stack clamp C2 and terminal T2 by auxiliary clamp member K4 and its bolts and compressing means L4. Thus not only is terminal T2 electrically connected to foil-bunch F2, but that foil-bunch is clamped in good thermal connection with lower stack-clamp C2, so that the latter is a stack-terminal as well as a stack-clamp, the effect being that terminal T2 is provided, via heat-dissipator C2, with substantial heat-dissipating area exposed from the interior of the stack. The above two foil clampings are permitted by cutting away part of (reducing) the width of the right-hand projecting foil-bunches (see F2, F3, Fig. 2), so that these two foil-bunches may pass by one another without interference.

Also in Figs. 1-2, upper foil-bunch F1 of upper stack section A is clamped to upper stack-clamp C1 by auxiliary foil clamp K2 and its bolts L2. And lower foil-bunch F4 of lower stack-section B is clamped to lower stack clamp C2 by auxiliary foil clamp K3 and its bolts L3. The individual armatures of F1 and F4 need not be reduced in width (see F1, Fig. 2) because one bunch, F1, goes to C1 and the other, F4, to C2, i. e., away from one another without crossing.

In the form of Figs. 1-3, the total thermal and electrical path from the distributed dielectric sheets of the clamped stack is greatly increased (resistance is reduced) as compared with the condensers of the prior art, this result being due to the above-described construction, shown most clearly in Fig. 1; while the extended external area of heat-dissipators C1, C2 relative to the external area of the stack, affords ample means for dissipating at a desirable low stack-temperature such increased amount of heat conducted from the interior of the stack.

In general, condensers embodying this invention are designed for moderate to high capacity of each clamped unit, .005 to .2 microfarad being obtained readily. With such range of capacity, almost any relation of capacity, voltage and current may be obtained by employing a plurality of units in various relations of series, parallel, or series-parallel.

The following has been a practical result of placing the distributed projecting foil-bunches in heat-conducting relation with one or more heat-dissipators of the below-specified order of exposed area. It has proven to be practicable to construct foil-stack condensers for high current duty with the same quantity of mica as for low current duty, and this whether the stack have only one or a plurality of sections. That is, by positively removing from the stack, via the foil-bunches and the heat-dissipators, the heat developed in the stack by the use of high currents, there is obviated all need of increasing the quantity of mica for the purpose of ridding the stack of the heat so developed. And while, with the invention, some mica may be added to assist in removing heat from the stack, the need of the same is removed in proportion to the efficiency of application of this invention. Prior to the use of said invention, the use of high currents required each section of a series-sectional stack to contain additional sheets of mica (more than was needed to obtain a desired capacity, in order to avoid over-heating by such currents, and in order to maintain a given desired capacity for the condenser it was necessary to divide the stack into serially-connected sections (or to increase the number of sections in a stack already comprising several series sections) when the number of sheets of mica in each

original section was increased to prevent over-heating. Hence the quantity of mica for a condenser of given capacity was greatly increased, due to the additional sheets in each section and to the additional sheets due to the addition of sections, so that a condenser for high current duty had very much more mica and a longer stack than a condenser for low current duty but of the same capacity.

10 By this invention, the number of sheets of mica in a condenser of given capacity can be kept substantially the same (for high or low current duty) whether the stack consist of a single section or of a plurality of sections connected in series. But the length of a stack provided with the invention (whether in a single section or a plurality of sections) is not necessarily less than that of a stack adapted by increase of mica to run without excessive heating under high current duty; because when the metal clamps for the condenser stack units are employed as in the invention, as the means removing heat via the projecting foil bunches, the metal of such clamps occupies more or less the same order of stack-length as when extra micas were employed for heat-distribution, being sometimes much greater due to the use of dissipating vanes on the clamps. In effect, therefore, the invention involves the substitution of metal for mica, the metal being very much cheaper. Various other advantages of the invention and of its various forms of embodiment have been specified above.

The efficiency of the invention in removing heat from a stack with which currents of very high amperage are employed may be dependent upon the efficiency of dissipation of heat from the metal masses which extract heat from the stack via the bunches of stack-distributed foils. That is, the maintenance of efficiency in continuously maintaining the conduction of heat from the interior of the stack at a desirably low stack-temperature, is dependent upon the continuous maintenance of heat-dissipation from the heat conducting metal masses.

The following general instructions are given for the guidance of the designer or constructor, relative to this important matter of exposed area of the heat-dissipating means of the invention. This is for condensers of various designs, and condensers for various services as to amperage frequencies and potential, in which the stack-generated heat may vary within wide limits. This is on the premise that the heat-dissipators are the stack-clamps substantially enclosing the stack and thermally connected via the foils thermally to the dielectric sheets distributed through the stack; and that substantially sole reliance is placed on the exposed surfaces of the clamps for the removal of heat from the stack at the desirable low temperature there-

of, it being kept in mind that a higher stack-temperature may be permitted by this invention on account of the permissive and preferred elimination of the previously customary paraffin embedment of the stack for high potential service. It should be noted that as the volume of the stack is increased (mica added for any reason), the exposed areas of heat-dissipation should be increased at a more rapid rate than the increase in external stack area corresponding to the increased stack volume. The object of the designer of a given condenser for desired conditions of service is to ensure the removal of all stack-generated heat without permitting the temperature of the stack to rise above a given upper limit. Therefore in designing a given condenser to embody the invention for given service, there will be calculated the amount of heat generated in the stack per unit of time, and the definite rate at which heat must be removed from the stack without "blowing" the stack or exceeding the upper limit of stack temperature. Since the invention provides adequate means of removing most rapidly from the interior of the stack, the heat generated therein (provided that after being so removed it is dissipated from the removing means), therefore the designer is concerned only in making sure to provide sufficient exposed area of the heat-dissipator in good thermal connection with the distributed foils. The designer therefore will provide such area sufficient to dissipate the removed heat at the rate at which he has calculated that it will be generated in the stack. And while, in general, such area exposed to the cooling medium will be of a substantially greater general order of magnitude than the exterior area of the electrostatically active portion of the stack itself, yet such area will vary within wide limits in various designs, on account of the several variables specified hereinbefore, including of course the kind of service and the amperage, frequency and potential to which the condenser is to be subjected. Within such wide limits there thus is provided a control by the designer of the stack temperature which he may desire to maintain. The area of the heat-dissipating means which is exposed to the cooling medium and thermally connected to the specified foils is, in any instance, that which causes dissipation of the heat generated inside the stack at the desired low stack-temperature, depending on the nature of the cooling medium, i. e., whether it is still air, a forced draft or a liquid circulation; and, of course, depending on the conditions of service, as to potential, amperage and frequency; this referring to the area of the heat-dissipating projections or fins or vanes, if and when they are employed as they preferably will be, especially when still air is the cooling medium.

Figs. 1 and 3, particularly Fig. 3 are diagrammatic in the sense that the stack-sheets are shown as separated for clearness, so that the thickness and external area of each stack 5 are greatly exaggerated. The armature-projections, which thermally connect the stack-units to the heat-dissipating members, need not be integral with the armatures such as the foils, but may be any equivalent thermal 10 connections between the armatures and the heat-dissipators. The preferred embodiment known is as shown.

I particularly point out and distinctly claim the part, improvement, or combination which I claim as my invention or discovery, as follows:—

1. The improvement in preventing undesirable temperature rise in the interior of an electrical condenser stack, which includes an 20 electrically insulating separator dividing the stack electrically into two units; two metal clamping members in clamping engagement with the ends of the stack, and having substantial areas exposed from the stack for 25 heat-dissipation; means holding said clamping members in their clamping positions; means insulating the clamping members from one another; wide armature-projections from armatures of each stack unit held in 30 thermal connection with one of said clamping and heat-dissipating members by lying flat against it; and wide armature-projections from other armatures of each stack unit held in thermal connection with the other 35 clamping and heat-dissipating member by lying flat against it; the stack-units being connected thermally in parallel with one another between the two clamping and heat-dissipating members.

40 2. The improvement in preventing undesirable temperature rise in the interior of an electrical condenser stack, which includes means dividing the stack electrically into two units; two metal stack-clamping members electrically insulated from one another, in clamping engagement with the ends of the stack, and having substantial areas exposed from the stack for heat-dissipation; armature-projections from armatures of each 45 stack-unit, and two clamping devices holding said armature-projections respectively in thermal connection with the two stack-clamping heat-dissipators; and armature-projections from other armatures of each 50 stack-unit and two clamping devices holding said other armature-projections respectively in thermal connection with the two stack-clamping heat-dissipators; the stack-units being connected thermally in parallel with 55 one another between the two stack-clamping heat-dissipators.

60 3. The improvement in preventing undesirable temperature rise in the interior of an electrical condenser stack, which includes means dividing the stack electrically into

two units; two metal stack-clamping members electrically insulated from one another, in clamping engagement with the ends of the stack, and having substantial areas exposed from the stack for heat-dissipation; 70 two terminals separate from the stack-clamping members and electrically insulated from one another, said separate terminals being located alongside the stack between the stack-clamping members and, respectively adjacent the respective stack-clamping members; armature-projections from armatures of the respective stack-units, and two clamping devices holding said armature-projections respectively in thermal connection with the 75 two stack-clamping heat-dissipators, and holding the two separate terminals respectively in mechanical connection with the stack-clamping heat-dissipators and in electrical connection with said armature-projections; and armature-projections from other armatures of the respective stack-units, and two clamping devices holding said other armature-projections respectively in thermal 80 connection with the two stack-clamping heat-dissipators, and holding the two separate insulated terminals respectively in mechanical connection with the stack-clamping heat-dissipators and in electrical connection with the 85 said last specified armature-projections.

4. The improvement in preventing undesirable temperature rise in the interior of an electrical condenser stack, which includes means dividing the stack electrically into two units; two metal heat-dissipating members electrically insulated from one another and having substantial areas exposed from the stack; two thermal connections extending from armatures of said respective stack-units; two thermal connections extending from other armatures of the respective stack-units; two clamping devices holding two of 100 said thermal connections respectively in thermal connection with one of said heat-dissipating members; and two clamping devices holding the other two of said thermal connections respectively in thermal connection with the other heat-dissipating member; the stack units being connected thermally in parallel with one another between the two heat-dissipating members.

5. The improvement in preventing undesirable temperature rise in the interior of an electrical condenser stack, which includes means dividing the stack electrically into two units; two metal heat-dissipating members electrically insulated from one another; and four wide armature-projections, two from each stack unit; means holding each armature projection flat-sided against a heat dissipating member so that each of the two heat-dissipating members is thermally connected to two of the armature-projections leading respectively from the two stack-units, whereby the stack-units are connected thermally in 110 115 120 125 130

parallel with one another to the two heat-dissipating members.

6. The improvement in preventing undesirable temperature rise in the interior of an electrical condenser stack, which includes means dividing the stack electrically into two units; two metal clamping members electrically insulated from one another, in clamping engagement with the ends of the stack, and having substantial areas exposed from the stack for heat-dissipation; and wide armature-projections extending between the respective stack-units and clamping members, and lying flat-sided against the clamping members thereby thermally connecting the stack-units in parallel with one another between the two clamping members.

7. The improvement in preventing undesirable temperature rise in the interior of an electrical condenser stack, which includes means dividing the stack electrically into two units; two terminals electrically insulated from one another and having substantial areas exposed from the stack for heat dissipation; and wide armature-projections extending between the respective stack-units and heat-dissipating terminals and lying flat-sided against the latter, and thermally and electrically connecting the stack-units in parallel with one another between the two terminals.

8. The improvement in removing heat generated in the interior of an electrical condenser stack, which includes means separating the stack into two electrical units; and two metal members having substantial areas exposed from the stack for heat dissipation, and arranged on the ends of the stack as clamping means therefor; an armature-projection from the first stack-unit in thermal and electrical connection with the first stack-clamping heat-dissipator adjacent said first unit; an armature-projection from the second stack-unit in thermal and electrical connection with the second stack-clamping heat-dissipator adjacent said second unit; an armature-projection from the second stack-unit in thermal and electrical connection with the first stack-clamping heat-dissipator; and an armature-projection from the first stack-unit in thermal and electrical connection with the second stack-clamping heat-dissipator; said last two armature-projections having reduced widths for passing by one another without interference.

9. The improved condenser stack which includes two stack units stacked together end to end and constituting a double stack, each stack unit including at least two foil armatures separated from one another by a dielectric sheet, and each of such two foils in each of the two stack units projecting out beyond the dielectric sheet between them; metal clamping members engaging the outer ends of the double stack; two metal terminals; and

four clamping devices clamping said four foil-projections in thermal and electrical connection with said metal clamping members and metal terminals; two of said four clamping devices clamping to one clamping member and one terminal, one of the foil-projections of one stack-unit, and clamping to said clamping member, one of the foil-projections of the other stack-unit; and the other two of said four clamping devices clamping to the other clamping member and other terminal, the other two of said four foil-projections of the two stack-units, whereby the two stack-units are connected in parallel thermally and electrically with one another between the two clamping members and two terminals.

10. The improved condenser stack which includes two condenser units stacked together end to end and constituting a double stack, each stack unit including at least two foil-armatures separated from one another by a dielectric sheet, and each of such two foils in each of the two stack-units projecting out beyond the dielectric sheet between them; metal clamping members engaging the outer ends of the double stack; and four clamping devices clamping said four foil-projections in thermal and electrical connection with said clamping members, and two of said clamping devices clamping to one clamping member, one of the foil-projections of one stack-unit and one of the foil-projections of the other stack-unit; and the other two of said four clamping devices clamping to the other clamping member, the other two of said four foil-projections of the two stack-units, whereby the two stack-units are connected thermally in parallel with one another between the two clamping members.

11. The improved condenser stack which includes two condenser units stacked together end to end and constituting a double stack, each stack unit including at least two foil armatures separated from one another by a dielectric sheet, and each of such two foils in each of the two stack units projecting out beyond the dielectric sheet between them; two metal terminals insulated from one another and having substantial areas exposed from the stack for heat-dissipation; and means clamping said four foil-projections in thermal and electrical connection with said terminals, one terminal being so connected with one of the foil-projections from one stack-unit and with one of the foil-projections from the other stack-unit, and the other terminal being so connected with the other two foil-projections of the two stack-units, whereby the two stack-units are connected in parallel with one another thermally and electrically between the two terminals.

12. The improved condenser stack which includes two stack units stacked together end to end and constituting a double stack, each stack-unit including at least two foil-

armatures separated from one another by a dielectric sheet, and each of such two foils in each of the two stack-units projecting out substantially half its width or more beyond

5 the dielectric sheet between them; and two heat-conducting and heat-dissipating members of metal insulated from one another and having extended heat-dissipating area exposed from the double stack; said four foil-

10 projections being thermally and electrically connected with said heat-dissipating members and lying flat-sided against them, one foil-projection from one stack-unit and one foil-projection from the other stack-unit being

15 connected to one of said heat-dissipators, and the other two foil-projections from the two stack-units being connected to the other heat-dissipators, whereby the two stack-units are connected in parallel with one another,

20 between the two metal heat-dissipators.

13. The improvement in removing heat generated in the interior of an electrical condenser stack, which includes means separating the stack into two electrical units; and

25 two terminals insulated from one another and having substantial areas exposed from the stack for heat-dissipation; the armatures of one of the stack-units being connected in parallel with the armatures of the

30 other stack-unit; and wide extensions of said armatures respectively lying flat-sided against each of said heat-dissipating terminals so that each is thermally and electrically connected with armatures in the two stack-

35 units which armatures are connected in parallel with one another.

14. The improvement in removing heat generated in the interior of an electrical condenser stack, which includes means electrically separating the stack into two units; and two terminals insulated from one another and having substantial areas exposed from the interior of the stack; a thermal and electrical connection between the first of said

45 heat-dissipating terminals and an armature of the first stack-unit; a thermal and electrical connection between the second of said heat-dissipating terminals and an armature of the second stack-unit; a thermal and electrical connection between said first terminal and an armature of said second stack-unit; and a thermal and electrical connection between said second clamping terminal and an armature of said first stack-unit.

55 In testimony whereof I hereunto affix my signature.

WILLIAM M. BAILEY.
